UNITED STATES PATENT OFFICE

161,122

COMBINED ILLUMINABLE RATTLE AND SUCTION CUP

Leo Packman, New York, N. Y.

Application January 20, 1950, Serial No. 7,363

Term of patent 3½ years

(Cl. D34—15)

To all whom it may concern:

Be it known that I, Leo Packman, a citizen of the United States of America, residing in New York city, county of New York, and State of New York, have invented a new, original, and ornamental Design for a Combined Illuminable Rattle and Suction Cup, of which the following is a specification, reference being had to the accompanying drawing, forming part thereof, wherein:

Figure 1 is a front elevational view of a combined illuminable rattle and suction cup showing my new design.

Figure 2 is a side elevational view.

Figure 3 is a rear elevational view, and

Figure 4 is a view similar to Figure 1 showing the central circular element pushed down upon the stem member to produce the rattle's illumination.

I claim:

The ornamental design for a combined illuminable rattle and suction cup, substantially as shown and described.

LEO PACKMAN.
